BUCKLE

Daniel I. Reiter, New York, N. Y., and James H. Arthur, Providence, R. I.; said Arthur assignor to said Reiter

Application August 2, 1933, Serial No. 683,264

13 Claims. (Cl. 24—186)

This invention relates to buckles of the type known as slide buckles, and which are adapted to slide on or to be secured to one part and to receive and secure the end of an adjusting strap in place.

5 The invention contemplates the provision of a buckle designed to be economically manufactured from a single piece of sheet metal and provided with simple and efficient means whereby the buckle may be readily attached to an article of 10 clothing and with integral means for gripping the strap or belt passed therethrough to maintain said strap or belt in its adjusted position.

15 The invention further contemplates the provision of means adapted to reinforce and strengthen the buckle and to serve the additional function of engaging and gripping the strap passed through the buckle. The invention further contemplates the provision of simple and efficient means for securing the buckle to a piece of 20 fabric such as part of an article of clothing.

The various objects of this invention will be clear from the description which follows, and from the drawings, in which,

Fig. 1 is a rear elevational view of one form 25 of our improved buckle.

Fig. 2 is a side view of the same.

Fig. 3 is a horizontal section, taken on the line 3—3 of Fig. 1 of the same.

Fig. 4 is a similar view of a modified form of 30 the same.

Fig. 5 is a rear view of a modified form of the buckle and particularly on the central bar thereof.

Fig. 6 is a similar fragmentary view of another 35 form of the member carrying the strap-engaging teeth.

Fig. 7 is a horizontal section of the same, taken on the line 7—7 of Fig. 6.

Fig. 8 is a similar view of a modified form of the same wherein the tooth-carrying member is 40 bent from the outermost edge of the buckle.

Fig. 9 is a view similar to Fig. 6 of another form of our invention wherein the teeth are shown aligned with each other.

Fig. 10 is a horizontal section of the same, taken 45 on the line 10—10 of Fig. 9.

Fig. 11 is a similar view, similar to Fig. 8 of a modified form of the member carrying the strap-engaging teeth.

Fig. 12 is a view similar to Figs. 6 and 9 but 50 showing a modified form of the buckle teeth.

Fig. 13 is a horizontal section of the same, taken on the line 13—13 of Fig. 12.

Fig. 14 is a view similar to Fig. 13 but showing 55 the strap-engaging teeth aligned with each other as in Fig. 9.

Fig. 15 is a similar view of another modified form of the member carrying the teeth, similar to Fig. 8 in that said member is bent from the outer edge of the buckle.

Fig. 16 is a view similar to Fig. 14 of another modified form of the member carrying the strap-engaging teeth bent similarly to the form of Fig. 15, in which the teeth are aligned in a manner similar to Fig. 14.

Fig. 17 is a front elevation of another form of 10 the buckle wherein the fastening means are made integral with the central bar of the buckle.

Fig. 18 is a side view of the same.

Fig. 19 is a front elevation of the prong clamping member used in connection with the buckle 15 of Fig. 17.

Fig. 20 is a horizontal section of the buckle shown in Figs. 17 and 18 but showing the buckle assembled with the clamping member of Fig. 19 and in its operative position.

Fig. 21 is a rear view of the same.

Fig. 22 is a horizontal section of the same, the parts, however, being shown in the positions which they assume prior to the assembly thereof.

Fig. 23 is a similar view of a modified form of 25 the same wherein the prong clamp, however, has been omitted and the prongs utilized to secure the buckle directly to the article to which it is attached.

Fig. 24 is a rear elevation of another form of 30 buckle wherein the attaching prongs are arranged to project from the ends of the buckle.

Fig. 25 is a similar view of a modified form of 35 the buckle wherein the attaching prongs are bent from the material of the buckle cross bar.

Fig. 26 is a similar view of another modified form of the buckle wherein two sets of attaching prongs are used, one set being arranged on each side of but adjacent the central bar.

Fig. 27 is a similar view of the prong clamp 40 used in connection with the buckle of Fig. 26.

Fig. 28 is a bottom plan view of the buckle of Fig. 26 as it appears assembled with the prong clamp of Fig. 27.

In the practical embodiments of our invention 45 which we have illustrated by way of example, we have provided in a one-piece buckle, a member adapted to reinforce the buckle and to carry the belt-engaging teeth thereon.

We have also provided novel means for securing 50 the buckle, when desired, to the fabric of which articles of clothing are usually made.

In that form of the invention shown in Figs. 1 to 3 inclusive, the buckle 30 is made of a single piece of sheet metal and is provided with a pair 55

of spaced transverse belt or strap-receiving slots 31 and 32. Transverse end bars as 33 and 34 are thereby provided, together with the central transverse or cross bar 35. Said bars are connected by the longitudinal or side bars 36 and 37 at their respective sides. Each of the end bars 33 and 34 is, however, extended and folded back on itself to provide the tooth-carrying members as 37a and 38, each of at least two thicknesses of material. As illustrated, said members 37a and 38 are integrally joined to the end bars and bent therefrom as by means of the integral respective bends 39 and 40. At the innermost edge 41 of each of the end bars is provided a series of serrations forming the preferably blunt teeth 42 on said edge.

As best shown in Fig. 3, the teeth 42 lie in substantially the same plane as the remainder of the member 37a. It will be understood, however, that the teeth may be bent at any desired angle to said member, as is for example shown in Fig. 4, wherein the teeth 43 are bent downwardly and inwardly of the slot 41 to insure the desired gripping of the strap or belt passed through the opening 31.

At the sides of the buckle, each of the side bars 36 and 37 is preferably continued for a short distance and the continuation bent rearwardly to form the guard flanges 43a and 44, respectively. Said flanges serve not only as a guide for the belt but also serve to reinforce the buckle as well as serving the additional purpose of concealing the short ends of the doubled members 37a and 38 from view. The central bar 35 is suitably slotted and/or perforated to provide means for receiving suitable securing means such as the rivets 29 shown in dash-dot lines, or other suitable fastening means, should it be desired to secure the buckle to the article of clothing. Towards this end, the slot 45 is provided substantially midway between the long edges of the bar 35. Said slot is constricted as at 46 and 47 and rounded as at 48 to provide a rivet receiving opening of not greater diameter than that of the greater part of said slot.

It will be understood, however, that the slot may be shaped in a great variety of different ways or that suitable spaced openings may be made in the bar 35 for the reception of the fastening means whether such means consists of rivets, sewing threads or any other means customarily used in the art. For example, as shown in Fig. 5, a series of suitably spaced circular openings as 49, 50 may be used to replace the slot 45 in the central bar 35, it being understood that the buckle 51 of Fig. 5 may be provided with the side guards 43a and 44, if desired, and with strap-engaging teeth at any desired point which may be found convenient, and as hereinafter described and hence not illustrated in Fig. 5.

In that form of the invention shown in Figs. 6 and 7, the teeth-carrying member 52, instead of being bent from the outer edge of the end bar 33, is bent from the inner edge thereof and is integrally connected to the end bar by means of the bend 53. Furthermore, instead of providing teeth on the free edge of the member 52 in the manner hereinbefore described in connection with Figs. 3 and 4, a series of suitable teeth as 54 may be pressed from the body portion of said bar 52 intermediate the edges thereof.

As shown in Fig. 6, each of the teeth 54 is pressed out from the material between a pair of intersecting cuts 55 and 56 to form a substantially triangular tooth. It will be noted that

while in Fig. 6, we have shown the teeth 54 in staggered relation, the teeth may be aligned with each other, as is for example shown in Figs. 9 and 10. There, the teeth 57, while being formed similarly to the teeth 54, are arranged in alignment on the teeth-carrying member 58.

It will also be understood that the teeth-carrying member 59, as shown in Fig. 8, may be bent from the outer edge of the end bar 33 and connected thereto by the integral bend 39, as described in connection with Figs. 3 and 4. The teeth 54 may be arranged in staggered relation as shown in Figs. 6 and 7, or said teeth may be aligned with each other in the member 59 as is shown in Fig. 11.

Hereinbefore, we have described teeth as 42 and 43 formed on the free edge of the tooth-carrying member or triangular teeth 54 arranged in staggered relation and pressed from the material of the bar intermediate its edges, as shown in Figs. 6 to 11 inclusive. It is to be noted, however, that the teeth may be otherwise formed on the teeth-carrying member, as is shown, for example, in Figs. 12 to 16 inclusive.

Referring to Figs. 12 and 13, the series of conical teeth 60 are arranged in staggered relation on the teeth-carrying bar 61 which is bent from the end bar 33 and integrally joined thereto by the bend 53. Said teeth are formed by the depression of the material of said member 61. The teeth, however, may be aligned, as shown in Fig. 14, at 62. Similarly, as shown in Fig. 15, the teeth-carrying member 63 may be bent from the outer edge of the end bar 33 and joined thereto by the integral bend 39 and provided with staggered teeth 60 similar to those of Figs. 12 and 13. In Fig. 16, the teeth-carrying member 63 is provided with aligned teeth 62.

It will be seen from the above that the teeth-carrying member may be arranged or bent in various ways from the remainder of the end bar, and that the teeth of said member may also be variously formed and variously arranged. Other arrangements and tooth forms will be obvious to those skilled in the art and hence need not be shown nor described in detail.

Referring now to Figs. 17 to 28 inclusive, we have there shown pronged means for efficiently securing the buckle to the article to which it is to be attached and to replace the openings 45, 49 and 50, shown in Figs. 1 and 5. In said Figs. 17 to 28, however, we have refrained from illustrating any strap-engaging teeth since it will be understood that any of the tooth forms or arrangements of the teeth or arrangement of the teeth-carrying bar heretofore described in connection with Figs. 1 to 16 inclusive may be applied to the buckle and attaching means of Figs. 17 to 28 or that such strap-engaging teeth may be entirely omitted, if desired.

In that form of attaching means shown in Figs. 17 to 22 inclusive, the central bar 65 of the buckle is provided with a series of edge prongs 66 adapted to be passed through the fabric 67 to which the buckle is to be permanently secured. It will be understood that the prongs may be turned over directly on to the under face of the fabric 67 as shown in Fig. 23. When so bent, the prongs have a tendency to tear through the fabric in the cases when such fabric is comparatively thin and non-resistant.

It is therefore preferred to clinch the prongs 66 about a prong clamping or retaining member 68 in the form of a combined anvil and retainer arranged on the under face of the fabric sheet 75

67. Said member 68 is provided with a lowermost anvil portion 69 concave upwardly and with a pair of prong-retaining members 70 and 71. Each of the prong-retaining members is preferably made integral with the respective ends 72 and 73 of the clamping member and is bent to a position above and into parallel relation with the anvil portion 69 to provide a space as 74 therebetween for the reception of the prongs. In order that the prongs may not be unduly long, the central bar carrying the prongs may be depressed below the plane of the remainder of the buckle if desired.

In assembling the buckle to the fabric, the member 68 is arranged on one side of the fabric and the buckle on the other side thereof. On pressing the buckle and clamping member together, the prongs 66 engage the upper concave surface of the anvil portion 69 and are thereby bent into the form shown in Fig. 21, the prongs entering the space 74 and being directed underneath and retained in place by the members 70 and 71 and drawing the clamping member 68 tightly against the under face of the fabric. It will be understood that the prongs 66 on one edge of the central bar 65 are during the clinching operation bent in one direction, that is, towards the left, while the corresponding prongs on the other edge of the bar are bent in the opposite direction, that is, towards the right.

The respective series of prongs on the bar 65 are therefore preferably arranged in staggered relation whereby a space as 75 is provided between adjacent prongs 66 to permit the bending thereto of the opposed prong on the other edge of the bar 65. It will be seen that the clamping member 68 serves not only as a retaining member for the prongs but serves also to bend said prongs into the proper position to secure the buckle to the article to which it is to be attached and also to conceal said prongs, as well as to prevent possible projection of sharp points on the prongs which might injure the user, and that said member further serves to provide a secure metallic engagement for the prongs instead of the fabric engagement shown in Fig. 23.

In Fig. 24, the prongs 76 are arranged longitudinally instead of transversely and while integral with the remainder of the buckle, they are preferably though not necessarily aligned with the central bar 77. Said prongs 76 are adapted to pass through the fabric and bent either on to the under face thereof or into a suitable clamping member similar to the member 68, and such as is shown for example, in Fig. 27 at 83.

In Fig. 25, the longitudinal prongs 78 are pressed from the material of the central bar 79 from between a pair of meeting cuts 80 and 81 made in said central bar.

As shown in Fig. 26, the prongs 82 may extend from the side bars of the buckle inwardly toward each other, it being understood that if desired, a series of prongs may be arranged to extend away from each other from the outer edge of the cross bar similar to the prongs 76. While the prongs 76 of Fig. 24, 78 of Fig. 25, and 82 of Fig. 26 may be used, if desired, without a clamping member, said prongs may also be used in connection with a suitable clamping member to preserve the fabric and to effect a more efficient attachment of the buckle to the fabric.

Such a clamping member is similar to the member 68 excepting that the prong retaining spaced member thereof is arranged transversely

of the clamping member instead of longitudinally thereof.

Referring to Fig. 27, the clamping member 83 used in connection with the prongs 76, 78 and 82 is provided with upwardly concave portions 84 and 85 adjacent the respective ends thereof. The recessed, depressed or concave portion 84 is further provided with the transversely arranged prong-retaining members 86 and 87, each integral with one of the edges of the member 83 and bent toward each other into spaced relation with the upper wall of the recess or depression 84. Similarly, the bars 88 and 89 are provided in spaced relation to the recess 85. The member 83 is made of sufficient width to permit the prongs of the buckle to engage the upper concave wall of the recess and to be clinched by said wall between the bars 86, 87, 88, 89 and the upper wall of the respective recesses 84, 85 in the manner hereinbefore explained in connection with the prongs 66 and clamping member 68 but in a direction at right angles to the previously described member 68.

It will be noted that in Fig. 26, the central bar 90 is arranged in substantially the same plane as that of the remaining buckle bars. The prongs 82, however, are depressed below said plane in the manner hereinbefore described in connection with the central bar 65 of Fig. 17. Similarly, the bars 77 and 79 of Figs. 24 and 25, respectively, with the prongs carried thereby or extending therefrom may also be depressed below the plane of the top face of the buckle though it will be understood that such depression is not essential.

It will be seen that we have provided a strong, efficient and durable buckle adapted to slide on a strap if desired or to be secured thereto, that the doubled or folded end bars reinforce the buckle and may if desired be provided with teeth of various forms and arrangements; that we have further provided simple means for efficiently securing the buckle to an article when it is desired to do so, and that we have provided a structure well adapted to meet the severe requirements of practical use.

While we have shown and described certain specific embodiments of our invention, it will be understood that we do not desire to limit ourselves thereto, but intend to claim our invention as broadly as permitted by the state of the prior art and the scope of the appended claims.

We claim:

1. A buckle formed of a single piece of sheet metal and slotted and including a pair of end bars, each of said end bars being folded under on itself to provide two parallel and coextensive thicknesses of material and strap-engaging teeth projecting from the under thickness, said teeth being rigid and blunt and arranged inwardly of the outermost end edges of the end bars to engage but not to pierce a strap sliding in the slots of the buckle.

2. A buckle of a single piece of sheet material having sides, ends, and a transverse bar separated by transverse belt-receiving slots from said ends and connecting said sides, each of said ends being folded under on itself to provide at least two thicknesses of material, a series of belt-engaging teeth projecting from the under thickness of material, and means adjacent the transverse bar for securing the buckle in place to a belt, said means being adapted to pass through the belt.

3. A buckle of sheet material provided with end bars and with a pair of transverse belt-receiving slots, each of the end bars being folded

- on itself to provide at least two parallel, coextensive and closely adjacent thicknesses of material joined by an integral rounded bend of less diameter than three times the thickness of said material, and rigid, blunt and non-piercing belt-engaging projections on the lower thickness of the material of said end bar.
4. A slide buckle of a single piece of sheet material having a transverse bar separated by a pair of spaced belt-receiving slots and including a pair of end bars, each of said end bars being folded on itself to provide at least two parallel, coextensive and closely adjacent thicknesses of material thereon, and blunt belt-engaging projections integral with the lower thickness of the material of the end bar and extending in a direction to grip a belt slidably passed through said slots, and slidable past the projections, said transverse bar being adapted to have a belt secured thereto.
5. A slide buckle of a single piece of sheet material having a pair of spaced belt-receiving slots therein and including a pair of end bars, each of said end bars being folded on itself to provide at least two coextensive thicknesses of material thereon, a series of belt engaging teeth projecting from each of the end bars, a transverse bar separating the slots, and means adjacent the transverse bar and adapted to pass through material to which the buckle is applied for securing the buckle to said material, said teeth being blunt and arranged to engage one surface of a belt slidably passed through the slots and on which the buckle is slidable.
6. A buckle having a pair of end bars and provided with belt-receiving slots, each of said end bars being folded on itself, and integral belt-engaging teeth depressed from the material of the lower folded portion of the end bar and arranged in position to grip a belt passed through and slidable in said slots.
7. A buckle having sides, ends, and a transverse bar separated by slots from the ends and connecting said sides, integral prongs on the buckle adapted to be passed through material to which the buckle is applied when the buckle is arranged on one face of said material, and prong-clinching anvil means adapted to be arranged on the other face of said material and to receive and bend the prongs, said means comprising an elongated, imperforate curved portion and an integral prong-retaining portion arranged in spaced relation and substantially parallel to and of substantially the length of the curved portion.
8. A buckle having an end portion folded on itself, and belt-engaging teeth integral with said folded portion, a central cross bar on the buckle, and means including bendable prongs integral with the cross bar for securing said buckle permanently in place to one face of a piece of material or the like other than the belt engaged by the teeth, and an anvil member adapted to be arranged on the other face of the material for receiving and bending the prongs.
9. In a slide buckle of a single piece of metal and provided with a pair of spaced transverse belt-receiving slots, a cross bar separating the slots and having means adapted to pass through

a piece of fabric whereby the buckle is securable to the piece of fabric, a pair of end bars parallel to the cross bar, each of the end bars being folded on itself to provide two coextensive, rigid thicknesses of material, one of said thicknesses terminating in a free edge, and rigid teeth projecting from one of said thicknesses into the path of a belt passed through said slots and slidable therein.

10. A buckle having an end portion folded on itself, belt-engaging teeth integral with said folded portion, an elongated substantially flat central cross bar on the buckle integral at its ends with the remainder of the buckle, prongs extending laterally from and integral with an edge of the cross bar and additional prongs extending laterally from the other edge of the cross bar and substantially parallel to said first-mentioned prongs.

11. A buckle having an end portion folded on itself, belt-engaging teeth integral with said folded portion, a central cross bar on the buckle integral at its ends with the remainder of the buckle, a prong extending laterally from one edge of the cross bar, a substantially parallel prong extending laterally from the other edge of the cross bar, and means for securing the buckle in place comprising a metallic anvil member for receiving and bending the prongs.

12. In a buckle, a transverse elongated central bar substantially parallel to the edges of the buckle, integral prongs on the buckle adjacent the bar, said prongs being adapted to be passed through material to which the buckle is applied when the buckle is arranged on one face of said material, and an elongated anvil member adapted to be arranged on the other face of the material to receive and bend the prongs and thereby to secure the buckle to said material, said anvil member comprising an elongated prong-engaging and bending part curved in one direction, and a pair of prong-retaining members, said prong-retaining members extending from and being integral respectively with opposite edges of the curved prong-bending part and extending toward each other in spaced relation to the curved part except at said opposite edges.

13. A buckle of generally rectangular outline having a transverse bar separated by a pair of belt-receiving slots, prongs extending laterally from the buckle and arranged in parallel planes, and an elongated prong-clinching and retaining member provided with a curved imperforate anvil part and with a pair of prong-retaining parts, said prong-retaining parts extending toward each other respectively from opposite edges of the curved part, the combined length of said prong-retaining parts being substantially the same as the length of said curved part, said prong-retaining part being spaced from the curved part except at the ends thereof, said anvil member cooperating with the prongs to secure the buckle to a sheet of material through which the prongs are passed on movement of the prongs and the member toward each other with the material therebetween.

DANIEL I. REITER.
JAMES H. ARTHUR.
